UNITED STATES PATENT OFFICE.

JOHN EYRE COOTE HOLMES, OF OTTAWA, ONTARIO, CANADA.

SKEE-FITTING.

1,372,752.

Specification of Letters Patent. Patented Mar. 29, 1921.

Application filed March 20, 1920. Serial No. 367,552.

To all whom it may concern:

Be it known that I, JOHN EYRE C. HOLMES, a citizen of the Dominion of Canada, residing at the city of Ottawa, in the county of Carleton and Province of Ontario, Dominion of Canada, have invented certain new and useful Improvements in Skee-Fittings, of which the following is a specification.

10 My invention relates to an improved skee-fitting, by means of which the boots of the user may be secured to the skee in such manner that there is substantially no lateral movement of either heel or toe, and the forward movement of the foot is absolutely in line with the axis of the runner of the skee.

15 The invention also comprises an improved elastic toe-strap.

The invention will be understood from 20 the accompanying description and drawings in which,—

Figure 1 is an elevation of a portion of the skee to which my device is attached;

Fig. 2 is a plan view of Fig. 1;

25 Fig. 3 is a sectional elevation on plane 4-4 of Fig. 2;

Fig. 4 is a detail of the attaching plate; and

30 Figs. 5 and 6 are sectional elevations of Fig. 4 on planes 5-5 and 6-6.

As shown in Figs. 1 and 2, a V-shaped frame V, preferably made of spring steel is provided near the apex or rear portion with a longitudinal slot S. The side por-

35 tions of the frame are turned down to lie against the sides of the body E of the skee, and are provided with eyes, through which is passed a bolt G, extending through a suitable opening in the body E. Side plates

40 F, are preferably used, and are screwed fast to the body E.

Additional openings, O, O, O, with corresponding holes through the body may be provided, so that the pivot bolt G, may be

45 moved forward or back to suitably adjust the location of the attaching plate V. A plate D, is secured preferably by rivets, to the sole of the boot, in front of the heel, and is provided with a nipple D' shaped

50 as shown in Figs. 5 and 6.

A toe-strap, C, preferably made in the shape of a coiled spring is secured to the ends of a bolt H, also passing through the side-plates and skee-body. An adjusting

55 plate "n," provided with spaced perforations, and a corresponding hook n', enable

suitable adjustment for varying widths of boot. If desired, a small piece of leather L can be attached under the toe-spring for protecting the foot in extreme cold weather. 60 The bolt H, may be moved forward or back to adjust the position of the toe-spring.

The mode of operation will be readily understood. To attach the foot to the skee, the foot is placed at right angles to the skee 65 as shown in Fig. 2, and the nipple D inserted into the slot S. By turning the foot through 90°, the V-piece is locked to the sole, after which the toe-spring is locked over the boot. 70

For use in deep soft snow, the fitting is advanced to the front-holes, thus tending to prevent the front of the skee being weighted down by the snow. The toe-spring may be used as a complete fitting, without the V- 75 piece. The spring toe-strap permits some forward and back movement; and the spring grips the foot sufficiently for all ordinary skeeing. When used in conjunction with the V-piece, as for jumping, it is impossible 80 for the skee to become detached from the foot.

I claim:

1. A skee-fitting including a flexible element having one end pivotally connected to 85 a skee and means for detachably connecting the other end of the said element to the sole of a boot, forwardly of the heel and intermediate the lateral edges of the sole.

2. A skee-fitting including a flexible element having one end pivotally connected to a skee and means for detachably connecting the other end of the said element to the sole of a boot, forwardly of the heel and intermediate the lateral edges of the 95 sole, said means including a part secured to the sole and means on said part and on the element forming a separable connection.

3. A skee-fitting comprising a link connected to a skee and having angular movement about its point of attachment, the link having an opening at its free end, an element adapted to be secured to the sole of a boot and having a head formed to pass through the opening when the boot is in 100 a position different from the normal running position and to be locked to the link when the boot is in normal running position.

105 In testimony whereof I affix my signature. 110

JOHN EYRE COOTE HOLMES.
